UNITED STATES PATENT OFFICE.

CHARLIE L. SMITH AND HARVEY B. HANDLEY, OF CHILDRESS, TEXAS.

LISTER.

Application filed November 4, 1924. Serial No. 747,805.

To all whom it may concern:

Be it known that CHARLIE L. SMITH and HARVEY B. HANDLEY, citizens of the United States of America, residing at Childress, in the county of Childress and State of Texas, have invented new and useful Improvements in Listers, of which the following is a specification.

The purpose of the invention is to provide a device for use in connection with cultivating machines to be drawn thereby and disposed in straddling relation to a row of plants, to weed the furrows and to agitate the surface soil; to provide a construction adjustable to vary the width thereof; and to generally simplify the construction of such appliances so that the likelihood of getting out of order will be reduced to a minimum.

With this purpose in view, the invention consists in the construction and combination of parts of which a preferred embodiment is illustrated in the accompanying drawings, wherein:

Figure 1 is a side elevational view showing the invention attached to a conventional form of cultivator.

Figure 2 is a central longitudinal sectional view through the invention.

Figure 3 is a top plan view of the invention, detached.

Figure 4 is a section on the line 4—4 of Figure 3.

Adapted particularly for use in connection with cultivators, the invention comprises the runners 1 which are connected by the yokes 2 so as to space the runners laterally for disposition in straddling relation to a row of plants. In order to provide adjustment for increasing or reducing the space between the runners, the yokes consist of angle members of which the shorter legs 3 are disposed in overlapping relation with registering holes 4 through which bolts 5 pass. By the proper selection of holes 4, the yokes may be adjusted to vary the spacing of the runners, as desired.

On the lower and forward edges, the runners are provided with shoes 6 and at the forward end carry the bars 7 for attachment to the plow beams 8 of a conventional form of cultivator 9. The shank bars 10 disposed vertically adjacent the forward ends of the runners, are secured to the latter by the fasteners 11 which also secure the forward yoke to the runners and are adapted for securing to the plow beams 8 by the straps

12 used to attach the plow when the invention is not employed in connection with a cultivator.

The runners 1 at the rear ends have attached to them the brace bars 14 disposed in divergent relation for connection with the beams 8 by the strap 15 normally serving to secure the plow to the beam. Each runner is provided with a laterally extending beam 16 carrying at its rear end a clamp plate 17 secured to the beam as by bolts 18. The clamp plate serves as a means for attaching a plow shank 19 carrying at its lower end a shovel 20. By means of the clamp plate 17, of which the bolts are spaced a material distance apart, the angular position of the plow shank with reference to the beam may be varied to suit the conditions of work.

To guard the plants in the regions of the shovels 20, the fenders 21 are provided, these fenders being carried at the extremities of the pivotal arms 22 secured to the runners and extending rearwardly therefrom. The fenders are united by a yoke 23 similar to the yokes 2 and adjustable in the same manner to provide for transversely increasing or decreasing the spacing between the fenders. The yoke 23 has connected therewith a chain 24 by means of which the fenders may be raised when desired. The chain 24 at its remote extremity connects with the cultivator at the top of the arch or "hobbles," as indicated at 25.

Positioned at intermediate points on the runners are the knives 26 which are bolted, as at 27, to the outer faces of the runners and extend outwardly therefrom and rearwardly with reference thereto. As the runners are advanced, the knives below the soil travel and sever the stalks of weeds and at the same time loosen the top soil which is taken up by the shovels and thrown toward the hill, the plants in which are protected by the fenders 21.

The device being connected to the cultivator by attachment to the plow beams thereof, may be raised and lowered by the beam adjusting attachment and can thereby be run at different depths in the earth to suit the conditions of operation.

The device or attachment is intended, in actual use, to be attached to an ordinary single row or double row riding cultivator and to depend beneath and between the beams or gangs of said cultivator and to be rigidly affixed to said beams by the draw bars

- 7 which extend from the front of the runners 1 to the forward ends of said beams, as shown in the drawings, and by the shank bars 10 which extend upward from points
- 5 near the front ends of said runners to connect by straps 12 to said beams and by brace bars extending upward from the rear ends of said runners 1 to the rear ends of said beams, and being so attached to said beams
- 10 by means of the connections aforesaid as to be readily adjustable as to depth at which the knives attached to the runners shall operate beneath the surface by means of the lever of the cultivator itself which raises
- 15 and lowers the gang beams ordinarily.

Being so rigidly and firmly attached to the plow or gang beams of the cultivator and depending between the pair of beams and the device being placed astride the rows of plants, the wheels of the cultivator will run in the middle and between the rows of plants and thereby avoid the crushing of the plants by the wheels and the runners operating in the furrows beside the row of plants will 25 tend to prevent lateral motion by sliding or slipping of the wheels of the cultivator and vice versa. The wheels will tend to hold the runners and knives and plows of the device in proper position relative to the row of plants and prevent crushing or plowing up 30 of the plants in the row.

Being so attached by means of the bars and the straps to the beams of the cultivator, the knives can be controlled as to depth 35 to which they operate in the soil and by means of the lever of the cultivator itself to which the device is attached can be kept underneath the surface of the soil in uneven ground, the knives cutting all the weeds and 40 stirring the soil around the plants and between the rows.

By reason of the rigid attachment of the device to the beams of the cultivator, as above stated, it is especially adaptable to 45 the cultivation of plants between lister furrows, the runners and sides of the fenders 21 preventing the loose soil stirred by the knives from covering the small plants to an undesired depth and at the same time by 50 reason of such rigidity of the beams, the device is suitable for the cultivation of rows of plants that have been planted on a level, the wheels of the cultivator holding the device in proper position with relation to the 55 rows of plants and preventing the device from any lateral motion which would tend to place the device or attachment out of proper position relative to the row of plants.

Because of the fixed attachment of the device to the cultivator, its weight and its consequent pressure on the ground and the friction load by reason thereof are borne in great 60 part by the wheels of the cultivator. The wheels of the cultivator and the runners 1 65 acting in the matter of carrying the load in

a reciprocal manner, each to the other, and the load or draft is lessened and the horse power for drawing the cultivator and the device is decreased to a great extent.

Because of the attachment of the device 70 to the beams 8 of the cultivator and the operator's seat being on the cultivator itself, the operator is raised to a position which is further removed from the dust of the field accompanying the use of the device and the 75 operation thereof is rendered more sanitary and comfortable. Because of the connection of the device to the beams of the cultivator in the manner shown, the depth at which the knives and plows thereof operate 80 beneath the surface is, by means of the lever of the cultivator itself, easily and readily controlled by the operator without stopping the machine or the operator leaving the seat, thereby rendering the device especially 85 adaptable to the cultivation of rows of crops in uneven ground and in ground that is not uniform in friability without loss of time.

Because of the rigidity of the device, the 90 runners, knives, fenders and plows will, by reason of the load being carried by the wheels of the cultivator, be easily held in proper position with relation to the row of plants and the knives will stir the soil and cut all 95 the weeds between the rows and will not be shunted to one side or the other on account of contact of the knives with tough weeds or spots in the soil that are not easily friable. Due to the load being carried on the wheels 100 of the cultivator and due to the reciprocal 105 action of the runners and the wheels in carrying the friction load, the general motion of the whole machine is rendered steady and true and swaying motion is prevented and the burden of the draft is rendered 110 steady and even. Also because of the rigidity of the device and the reciprocal action of the wheels of the cultivator and the runners 115 in carrying the load and in holding the device in proper position, the device is especially 120 adaptable to the cultivation of listed ground before planting, stirring the soil and cutting all weeds between the rows.

Further, by reason of the rigidity of the 125 device relative to the cultivator and the consequent control of the depth at which the plows and knives run beneath the surface of the soil, the range of the use of the device with relation to the size and height of the plants in the rows is increased, enabling the operator to use the device for the cultivation of plants of different sizes and heights.

The shank bars are to be made of either round or flat steel or iron to fit any and all 130 different makes of cultivators, while the runners 1 may be constructed of wood or metal which in either case are reinforced by the shoes or metal straps 6. However, should the runners 1 be constructed of wood, the shoes 6 are consequently made of heavier

material than in case of metal runners in order to withstand wear and render the runners more durable.

The invention having been described, what is claimed as new and useful is:

1. In an attachment for single or double row riding cultivators, the combination with beams carried by the cultivator, of runners adapted for operating in the furrows beside a row of plants, means depending from the beams for rigidly suspending the runners, draw bars attached to the forward ends of the beams and extending rearwardly and downwardly and in turn connecting with the forward ends of the runners to relieve rearward strain upon the suspension means, and adjustable yokes between and rigidly connecting the runners which, together with the suspension means, insures rigidity, thereby preventing lateral motion by slipping and sliding of the cultivator wheels, and vice versa.

2. The combination with the structure in claim 1, of wear shoes secured to the sides of the runners immediately adjacent their lower longitudinal and forward edges, and knives secured to the remote sides of the runners for operation beneath the surface of the soil for cutting weeds and stirring the soil around the plants and between the rows.

3. In an attachment for single or double row riding cultivators, the combination with beams carried by the cultivator and provided with straps on their remote sides, of shank bars connected to the beams by the straps and carrying spaced runners at their lower portions, the shank bars acting to prevent lateral motion by sliding and slipping of the cultivator wheels and vice versa, arched yokes between and connecting the runners, insuring their rigidity, whereby the prevention of said lateral motion is assured, thereby holding the runners operating in the furrows beside the row of plants, and draw bars operatively connected to the forward ends of said beams and extending rearwardly and downwardly and operatively connec-

ting with the forward ends of said runners, thereby relieving rearward strain upon the shank bars and further insuring rigidity. 50

4. The combination with the structure in claim 3, of wear shoes affixed adjacent the end and the bottom edges of the runners, and knives affixed to the remote sides of the runners and extending rearwardly and laterally for operation beneath the soil and cuttings weeds and stirring the soil around the plants. 55

5. In an attachment for single or double row riding cultivators, the combination with parallel beams operatively mounted at their forward ends on the cultivator for fulcrumming movement, of rigidly spaced parallel runners rigidly suspended from the beams below and between them, whereby they may operate in the furrows beside the rows of plants, said runners being structurally prevented from lateral motion by sliding or slipping of the cultivator wheels and vice versa. 60

6. The combination with the structure in claim 1, of wear shoes secured to the sides of the runners immediately adjacent their lower longitudinal and forward edges, and knives secured to the remote sides of the runners for operation beneath the surface of the soil for cutting weeds and stirring the soil around the plants and between the rows. 65

7. In testimony whereof they affix their signatures. 70

CHARLIE L. SMITH.
HARVEY B. HANDLEY.
